TRANSFER DEVICE

Otto F. Smetana, Philadelphia, Pa., assignor to
 Textile Machine Works, Wyomissing, Pa., a
 corporation of Pennsylvania

Application August 17, 1934, Serial No. 740,239

22 Claims. (Cl. 66—148)

This invention relates to a novel and improved transfer or topping device for knitting machines, and particularly to a transfer bar for topping stocking blanks, for example, pressed-off leg blanks, onto the needles of a legger knitting machine.

In knitting stocking blanks on a legger machine, it occasionally happens that breakage of the yarn occurs, or that the yarn package feeding the body 10 yarn from which a leg blank is being knit becomes depleted, resulting in a "press-off", which pressed-off portion of the blank is topped on the needles of a stationary bar in a topping machine, and then transferred to the topping points 15 of a transfer bar by means of a knockover bit bar in a manner well known in the art.

When the pressed-off blank is transferred from the points of the transfer bar to the needles of the legger machine for completion of the blank, the 20 transfer bar must be held in the correct position for the loops to be transferred properly and to prevent dropped loops. Heretofore, this operation has required a high degree of skill and judgment on the part of the topper or operator. Not only 25 must the points of the transfer bar be correctly aligned with the proper needles in a coursewise direction so that the fabric loops will be topped on those needles to which the yarn will be fed in the next succeeding course, but also the elevation 30 of the transfer bar relative to the needles must be accurately determined and maintained to cause the transfer, or topping, points to properly enter the needle grooves to avoid splitting or dropping the loops.

An object of the invention is to provide a transfer bar having means for quickly and accurately aligning the topping points with the proper needles, and by means of which the topping operation does not require a high degree of skill 40 and judgment and may be performed by relatively inexperienced operators, notwithstanding that the probabilities of dropped or split loops are practically eliminated.

Another object is the provision of a device of 45 the character stated, that does not require the addition of parts to the usual legger machine and thus does not complicate the machine.

A further object is to provide a transfer bar having suitable means for guiding and aligning the topping points of the bar with the needles of a knitting machine and for determining and maintaining a predetermined elevation of the points relative to the needles during the topping-on operation.

55 Another object is to provide a device of the

character described, which is simple in construction and can be made at a low cost, and which may readily be attached to conventional point bars for transferring fabric to the needles of a straight knitting machine.

With these and other objects in view, which will become apparent from the following detailed description of the illustrative embodiments of the invention shown in the accompanying drawings, my invention resides in the novel elements of construction, devices and combination of parts in cooperative relationship, as herein-after more particularly set forth in the claims.

In the drawings:

Figure 1 is a perspective view of a topping machine, having inserted therein a transfer bar constructed in accordance with my invention;

Fig. 2 is a fragmentary view, looking in the direction of the arrow A in Fig. 1, of certain parts of the topping machine and transfer bar;

Fig. 3 is a perspective view of the transfer bar, showing certain guiding and positioning elements thereof in inactive position;

Fig. 4 is a view similar to Fig. 3, showing the guiding and positioning elements in active position for topping a stocking blank onto the needles of a legger;

Fig. 5 is an enlarged sectional view, taken substantially along the line 5—5 of Fig. 4, showing certain details of the guiding and positioning elements of the device;

Fig. 6 is an enlarged cross sectional view, taken along the line 6—6 of Fig. 4, showing other details of the guiding and positioning elements;

Fig. 7 is an enlarged perspective view of one of the guiding and positioning elements apart from the transfer bar;

Fig. 8 is a perspective view showing various elements of a knitting section of a legger machine, with the transfer bar in operative position for a topping operation; and

Figs. 9 to 13, inclusive, illustrate successive positions of the transfer bar and knitting needles during the topping operation.

Referring particularly to Fig. 1, there is shown a topping machine 15 of conventional construction, having inserted therein a transfer bar for the purpose of transferring thereto a knitted stocking leg blank press-off which has previously been topped on the stationary needle bar 50 of the topping machine, the blank being omitted in the drawings more clearly to show the various parts of the devices. The topping machine comprises right and left end frames or stands 17 and 18 mounted on a base 16, the stands carrying at 55

the upper ends thereof a rock shaft 19 journaled in bearings 20, the rock shaft having secured to the ends thereof and movable therewith transfer bar holders 22 having the ends 22a adapted to seat and align a transfer bar during the transfer operation. Pivotaly connected at 26 to the stands is a swinging frame 27 which forms a supporting bed for the knockover bits 28, by means of which the transferring operation is effected. Secured to the end frames, as by cap screws, not shown, is a needle bar or bed 21 supporting a series of topping needles 24 (see Fig. 2) clamped to the needle bed by clamping plates 25.

Whenever a press-off occurs in knitting leg blanks on a stocking knitting machine, the pressed-off portion of the blank is topped on the needles of a stationary bar 21 by a topper or operator, at which time the transfer bar holders 22 are raised, in a counterclockwise direction, as viewed in Fig. 2, in order to facilitate the topping operation, in a manner well known in the art. After the blank is topped on the topping needles, the transfer bar holders 22 are lowered to the position shown in the figures, and the ends of the transfer bar 31 inserted in the seating and guiding portions 22a of the holders which accurately align the points of the transfer bar with the proper topping needles. By moving the handle 29 forward, the swinging frame 27, carrying the knockover bits 28, is moved forwardly, thus stripping the fabric from the topping needles onto the transfer or topping points 33 of the transfer bar, thereby to enable the fabric to be transferred to the needles of a knitting section of a legger.

A legger has no means for guiding the transfer bar relative to the needles of the machine, and heretofore in topping press-offs on the needles of the machine for completion of the leg blank, it has been necessary for the topper or operator to manually hold the transfer bar in the correct position, and at the proper elevation, during the topping-on operation—a rather difficult feat. In accordance with the present invention, however, means are provided whereby the transfer bar 31 will be held in the correct position and maintained at the proper elevation relative to the needles, to insure that the transfer or topping points will properly enter the needle grooves, and avoid splitting or dropping the loops.

Figs. 3 to 7 show details of the transfer bar including means for positively maintaining the bar at the proper elevation during the topping operation. The bar comprises a transfer or topping bed 32 in which the points 33 are seated, the points being firmly held in position by means of a clamp bar 34 secured by screws 35 to the bed 32. Secured to the transfer bar bed are two members, each manually movable to active or inactive position, shown in the specific embodiment illustrated as arms 36 pivotally mounted at 37 and manually rotatable into active and inactive positions, the arms each carrying at one end 36a thereof a member or abutment 38 which, in the present instance, is detachably secured thereto by screws 39, altho, if desired, the member 38 or equivalent may be integral with its supporting member 36.

In Fig. 3 the arms 36 and members 38 are shown in inactive position, whereby they do not interfere with the operation of the topping machine. After a leg blank has been transferred to the points 33 of the transfer bar, however, members 36 are manually rotated, in a clockwise direction as viewed in Figs. 3 and 4, and turned

to the position shown in Fig. 4, whereby the members 38 provide aligning and guiding surfaces when the blank is topped on the needles of the knitting machine.

In order to maintain the arms 36 in either their active or inactive position, there is provided, in the form illustrated, a detent ball 41 seated in an apertured portion 42 of each arm 36, the ball 41 being biased inwardly, toward the topping point bed 32, by a spring 43 secured to the arm 36 in any suitable manner, as by a screw 44. In the inactive position shown in Fig. 3, balls 41 coat with detents or recessed portions 45 in the topping point bed, Figs. 4 and 5, and in active position the balls 41 coat with detent portions 46 of the bed. Stop means are provided for limiting the travel of the pivoted arms when moved to their active position, this means preferably, altho not necessarily, comprising protuberances or studs 47 secured to the topping point bed 20 and adapted to coat with recessed portions 48 in the arms 36.

Fig. 8 shows one knitting section of a legger machine, comprising a needle bar 51, a bank of needles 52 secured by clamping member 53 to the needle bar, and a sinker head assembly 54 comprising sinkers 56 and dividers 57 and verge plate 58. Positioned adjacent to the knitting needles are two horizontally disposed machine elements 62 and 63, shown in the present instance as the bridges used for supporting the welt bar preliminary to the welt turning operation. These bridges provide smooth plane surfaces on which the guiding and supporting means 38 of the transfer bar rest during the topping-on operation.

Figs. 9 to 13 illustrate various steps in sequence during the topping-on operation. In Fig. 9 the transfer bar is shown with the guiding and supporting member 38 at one end thereof resting on the bridge 62, it being understood that the other member 38 rests on and coacts with bridge 63 in like manner. With the fabric f on the transfer or topping points 33, the topping points are substantially parallel to the knitting needles 52 due to the angle of the surface 38b of members 38. At this time needle bar 51 has been laid out, in a manner well known in the art, to a position such that the needles are adjacent to the ends of the knockover bits 64.

The transfer bar is now manually rotated, usually by the knitting machine operator, to the position shown in Fig. 10, so that it rests on one edge of the surface 38b, at which time the ends of the points 33 have entered the grooves of needles 52. The needles are now manually moved, toward the presser edge 60, to knitting position, thus causing the needles and points to assume the position shown in Fig. 11, at which time the transfer bar is permitted again to rest on the plane surfaces 38b, of members 38.

The machine is now turned, usually by hand, until the needles rise and enter the loops on the topping points, at which time the points and needles abut the presser edge, as shown in Fig. 12. The continued rise of the needles causes the same to come up under the transfer bar and raise the bar above the knockover bits, after which the needles move away from the presser edge, as in their normal path of movement, completing the topping-on operation and releasing the transfer bar in the manner shown in Fig. 13.

In many instances it may be found unnecessary to utilize the surfaces 38a of the members 38 as

means for aligning the topping points relative to the knitting needles in a coursewise direction; also, the shape or size of the members 38, or the contour of their surfaces 38b, may be changed to 5 coat with machine elements other than the bridges of the knitting machine, or for any other purpose.

While I have shown and described my invention in connection with the transfer of fabric from 10 a topping machine, it can also be used for various other purposes requiring alignment of a point bar with the needles of a knitting machine, as, for example, topping-on separately formed welts, or in the turning of welts on a knitting machine. 15

Of course, the improvements specifically shown and described, by which I obtain the above results, can be changed and modified in various ways without departing from the scope of the invention herein disclosed and hereinafter claimed. 20

I claim:

1. A device of the character described, for use with a straight knitting machine having certain machine elements adjacent to the needles thereof, 25 comprising a bar, a series of points on the bar for engagement with said needles and guide means for coaction with said machine elements to align said points with the needles while placing fabric thereon, said guide means being movable on the 30 bar.

2. A topping device, for use with a straight knitting machine having certain machine elements adjacent to the needles thereof, comprising a series of topping points for engagement with 35 said needles and gauge means for coaction with said machine elements for maintaining a predetermined elevation of said points relative to the needles during the topping-on operation.

3. A topping device, for use with a straight knitting machine having certain machine elements adjacent to the needles thereof, comprising a series of topping points for engagement with 40 said needles and means for coaction with said machine elements to align said points with the needles and to maintain a predetermined elevation of the points relative to the needles during the topping-on operation.

4. A topping device, for use with a straight knitting machine having certain machine elements adjacent to the needles thereof, comprising a series of topping points for engagement with 45 said needles and means for coaction with said machine elements for supporting the device and the topping points thereof at a predetermined elevation relative to the needles during the topping-on operation.

5. A topping device, for use with a topping machine having topping needles and a straight knitting machine having certain machine elements adjacent to the knitting needles thereof, said device including a series of topping points for engagement with the needles of the topping and knitting machines, and having movably mounted means operable in one position to engage said machine elements for supporting the device and the topping points thereof at a predetermined elevation relative to the knitting needles during the topping-on operation, said means being manually movable to another position when the device is inserted in the topping machine. 70

6. A topping device, for use with a topping machine having topping needles and a straight knitting machine having certain machine elements adjacent to the knitting needles thereof, 75

said device including a series of topping points for engagement with the needles of the topping and knitting machines, and having turnably mounted means operable in one position to engage said machine elements for supporting the device and the topping points thereof at a predetermined elevation relative to the knitting needles during the topping-on operation, said means being manually turnable to another position when the device is inserted in the topping machine. 5

7. A topping device, for use with a topping machine having topping needles and a straight knitting machine having certain machine elements adjacent to the knitting needles thereof, said device including a series of topping points for engagement with the needles of the topping and knitting machines, and having movably mounted means operable in one position to engage said machine elements for supporting the device and the topping points thereof at a predetermined elevation relative to the knitting needles during the topping-on operation, said means being manually movable to another position when the device is inserted in the topping machine, and means for retaining said means in either of said 20 positions. 15

8. A transfer bar, for use with a topping machine having topping needles and a straight knitting machine having horizontally disposed machine elements adjacent to the needles of each 30 knitting section thereof, said bar comprising a topping point bed having a series of topping points mounted therein and abutments for engagement with said machine elements to support the transfer bar at a predetermined elevation 35 relative to the knitting needles during the topping-on operation.

9. A transfer bar, for use with a topping machine having topping needles and a straight knitting machine having horizontally disposed machine elements adjacent to the needles of each knitting section thereof, said bar comprising a topping point bed having a series of topping points mounted therein, a plurality of members manually movable to active and inactive positions, 40 and abutments carried by the movable members and operative in said active position for engagement with said machine elements to support the transfer bar at a predetermined elevation relative to the knitting needles during the topping- 50 on operation. 45

10. A transfer bar, for use with a topping machine having topping needles and a straight knitting machine having horizontally disposed machine elements adjacent to the needles of each knitting section thereof, said bar comprising a topping point bed having a series of topping points mounted therein, pivotally mounted members adjacent to the ends of the bar and rotatable to active and inactive positions, and abutments carried by said pivotally mounted members operative in said active position for engagement with said machine elements to support the transfer bar at a predetermined elevation relative to the knitting needles during the topping- 60 on operation. 65

11. A transfer bar, for use with a topping machine having topping needles and a straight knitting machine having horizontally disposed machine elements adjacent to the needles of each knitting section thereof, said bar comprising a topping point bed having a series of topping points mounted therein, a plurality of members each manually movable to active and inactive 70 positions, resilient means for retaining said 75

members in either of said positions, said members having means operative in said active position for engagement with said machine elements to support the transfer bar at a predetermined elevation relative to the knitting needles during the topping-on operation.

12. A transfer bar, for use with a topping machine having topping needles and a straight knitting machine having horizontally disposed machine elements adjacent to the needles of each knitting section thereof, said bar comprising a topping point bed having a series of topping points mounted therein, a plurality of members each manually movable to active and inactive positions, spring pressed detent means for retaining said members in either of said positions, said members having means operative in said active position for engagement with said machine elements to support the transfer bar at a predetermined elevation relative to the knitting needles during the topping-on operation.

13. A transfer bar, for use with a topping machine having topping needles and a straight knitting machine having horizontally disposed machine elements adjacent to the needles of each knitting section thereof, said bar comprising a topping point bed having a series of topping points mounted therein, a plurality of members each manually movable to active and inactive positions, resilient means for retaining said members in either of said positions, said members having means operative in said active position for engagement with said machine elements to support the transfer bar at a predetermined elevation relative to the knitting needles during the topping-on operation, and stop means for limiting the travel of the members when moved to said active position.

14. A transfer bar, for use with a topping machine having topping needles and a straight knitting machine having horizontally disposed machine elements adjacent to the needles of each knitting section thereof, said bar comprising a topping point bed having a series of topping points mounted therein and abutments for engagement with said machine elements to support the transfer bar at a predetermined elevation relative to the knitting needles during the topping-on operation, the supporting surfaces of said abutments being so arranged that when they are placed on said machine elements the topping points will be substantially parallel to the knitting needles, the supporting surfaces enabling the transfer bar to be rocked into a position such that the points enter the needle grooves while the bar is maintained at the required elevation.

15. A transfer bar, for use with a topping machine having topping needles and a straight knitting machine having horizontally disposed machine elements adjacent to the needles of each knitting section thereof, said bar comprising a topping point bed having a series of topping points mounted therein and abutments for engagement with said machine elements to support the transfer bar at a predetermined elevation relative to the knitting needles during the topping-on operation, the supporting surfaces of said abutments lying in a plane disposed at an angle relative to the plane of the series of points such that when the supporting surfaces are placed on said machine elements the topping points will be substantially parallel to the knitting needles, the edges of the supporting surfaces enabling the transfer bar to be rocked into a position such that the points enter the needle

grooves while the bar is maintained at the required elevation.

16. A transfer bar, for use with a legger knitting machine having welt-bar supporting bridges adjacent to the needles of each knitting section thereof, said bar comprising a topping point bed, a clamp member detachably secured to the bed, topping points mounted in said bed and secured thereto by said clamp member, two arms pivotally mounted adjacent the opposite ends, respectively, of said bed and manually rotatable to active and inactive positions, abutments at the ends of said arms and operative in said active position for engagement with said bridges to support the transfer bar at a predetermined elevation relative to the knitting needles during the topping-on operation, and protuberances on said bed for engagement with said arms to limit the travel thereof when moved to said active position.

17. A transfer bar, for use with a legger knitting machine having welt-bar supporting bridges adjacent to the needles of each knitting section thereof, said bar comprising a topping point bed, a clamp member detachably secured to the bed, topping points mounted in said bed and secured thereto by said clamp member, two arms pivotally mounted adjacent the opposite ends, respectively, of said bed and manually rotatable to active and inactive positions, spring pressed detent means carried by said arms and coacting with the bed to retain the arms either in active or inactive position, abutments at the ends of said arms and operative in said active position for engagement with said bridges to support the transfer bar at a predetermined elevation relative to the knitting needles during the topping-on operation, and protuberances on said bed for engagement with said arms to limit the travel thereof when moved to said active position.

18. A transfer bar, for use with a legger knitting machine having welt-bar supporting bridges adjacent to the needles of each knitting section thereof, said bar comprising a topping point bed, a clamp member detachably secured to the bed, topping points mounted in said bed and secured thereto by said clamp member, two arms pivotally mounted adjacent the opposite ends, respectively, of said bed and manually rotatable to active and inactive positions, detent balls carried by said arms and coacting with detent surfaces on said bed to position and retain the arms either in active or inactive position, abutments at the ends of said arms and operative in said active position for engagement with said bridges to support the transfer bar at a predetermined elevation relative to the knitting needles during the topping-on operation, said arms having apertured portions, and studs projecting from said bed for engagement with the apertured portions of the arms to limit the travel thereof when moved to said active position.

19. A guide device adapted to be secured to a point bar, said device comprising movable guide means to occupy one position relative thereto for aligning the point bar relative to the needles of a straight knitting machine while placing fabric thereon and another position when receiving the fabric for so placing it.

20. A guide device adapted to be secured to a point bar, said device comprising a guide member having an inclined contact surface for engagement with horizontally disposed machine elements adjacent to the needles of a straight

knitting machine and adapted to incline the points of the point bar at an angle such that they are substantially parallel with said needles.

21. A guide device adapted to be secured to a point bar, said device comprising a guide member for aligning the point bar relative to the needles of a straight knitting machine while placing fabric thereon, a support for said guide member, and means for mounting said support on said point bar for movement between different positions thereon in different operative positions thereof.

22. A guide device adapted to be secured to a point bar, said device comprising a guide member for aligning the point bar relative to the needles of a straight knitting machine while placing fabric thereon, a support for said guide member, means whereby said support is adapted to be movably mounted on said point bar, and means for maintaining the guide member in a plurality of positions on the point bar.
